UNITED STATES PATENT OFFICE.

EMMIT G. LATTA, OF FRIENDSHIP, NEW YORK, ASSIGNOR TO THE POPE
MANUFACTURING COMPANY, OF PORTLAND, MAINE.

VELOCIPED-E-SADDLE.

SPECIFICATION forming part of Letters Patent No. 376,892, dated January 24, 1888.

Application filed January 24, 1887. Serial No. 225,248. (No model.)

To all whom it may concern:

Be it known that I, EMMIT G. LATTA, of Friendship, in the county of Allegany and State of New York, have invented new and 5 useful Improvements in Velocipede-Saddles, of which the following is a specification.

This invention relates to that class of velocipede-saddles which are suspended at their front and rear ends, and has for its object to 10 produce a durable and elastic saddle which can be easily adjusted forwardly or backwardly and vertically, and in which the width of the rear portion of the seat can be increased or reduced, and which can be easily repaired.

15 My invention consists of the improvements which will be hereinafter fully described, and pointed out in the claims.

In the accompanying drawings, Figure 1 is a longitudinal sectional elevation of a velocipede-saddle provided with my improvements. 20 Fig. 2 is a cross-section in line $x-x$, Fig. 1, looking forward. Fig. 3 is a fragmentary top plan view showing the front portion of the saddle in a horizontal section taken in line $y-y$, Fig. 25 1. Fig. 4 is a top plan view, partly in section, of the support of the rear spring. Fig. 5 is a vertical cross-section in line $z-z$, Fig. 1, looking forward. Fig. 6 is a vertical cross-section in line $w-w$, Fig. 1, looking forward. Fig. 7 30 is a side elevation of the front saddle-support, showing the tubular screw-nut reversed.

Like letters of reference refer to like parts in the several figures.

A represents the backbone or reach of a velocipede; a , the flat-sided neck formed at the front end of the reach, and A' the steering-head.

B represents the seat, constructed of leather or other flexible material.

40 b represents the metallic pommel-plate, secured to the under side of the front portion of the seat by rivets b' , which pass through ears b'' , formed at the rear end of the pommel-plate. The front portion, b'' , of the latter has its sides 45 curved to form a longitudinal socket, in which is arranged a spring, C, of rubber or other suitable material. A spiral spring may be used, if desired.

D represents the pommel support or stand- 50 ard, which straddles with its bifurcated lower

portion the neck a , and is pivoted thereto by a horizontal bolt, d. The two jaws d' of the bifurcated lower portion of the support D are connected by a cross-piece or transverse bow, d'' , which rests on the backbone in rear of the neck and holds the support in an upright position. The upper portion, d'' , of the support D is provided with an external screw-thread, to which is applied a tubular screw-nut, E, which is provided near one end with a perforated ear or lug, e.

F is a horizontal bolt provided with a bifurcated front portion, f, which straddles the tubular nut E, and is pivoted to the ear e by a horizontal bolt, f' . The bolt F extends rearwardly through the pommel-plate b and spring C, and is provided at the rear end of the spring with a washer, g, and screw-nut g' .

Upon detaching the support D from the neck and turning it in the nut E the elevation of the 70 pommel can be adjusted to suit the requirements of the rider. In the position of the screw-nut E represented in Fig. 1 the pivot f' is arranged at the upper end of the nut and on the front side of the latter. Upon unscrewing the 75 support D from the nut the latter can be reversed on its pivot, as represented in Fig. 7, whereby the bolt F is adjusted downwardly and backwardly, the pivot f' now being located at the lower end of the nut and on the rear side 80 thereof. The arrangement of the pivot f' at one end of the nut affords, therefore, a greater range of adjustment than a pivot located at the middle of the nut. The saddle can be adjusted still farther back, if greater safety be required, by loosening the nut g' at the rear end of the bolt F. The nut g' permits the tension 85 of the spring C to be nicely regulated.

H represents the rear spring, composed of two similar and separate branches, h, having 90 their lower portions provided with coils h' .

I represents a supporting-plate secured to the upper side of the backbone and provided on its sides with longitudinal grooved seats i, in which the coils h' are supported.

J represents a transverse clamping plate or bar bearing on the coils h' above the base-plate I, and provided on its under side with grooved seats j, which rest on the coils and hold the plate against lateral displacement.

K represents a clip, which embraces the lower side of the backbone, and has its legs passed through openings in the clamping-plate, and provided above the latter with screw-nuts k, 5 whereby the clamping-plate J, spring H, and supporting-plate I are firmly secured to the backbone.

The lower and inner portions of the branches h of rear spring extend forwardly over the supporting-plate I, and are provided at their front ends with inwardly-projecting portions m m, arranged in line with each other, and provided with right and left screw-threads.

M represents a screw-sleeve or coupling, 15 which connects the threaded lower ends, m m, of the spring branches.

N represents an adjusting screw, which passes through the screw-sleeve M, and which is arranged in a vertical plane and about at right angles to the backbone. The lower end of the screw N rests upon the supporting-plate I and holds the screw-nut M at the desired elevation. The threaded end portions m of the spring branches are notched at their abutting 25 ends, and the screw N passes through the space formed by these notches, as clearly represented in Fig. 4, thereby preventing the nut M from turning on the threaded portions m when the screw N is in place. By turning the screw N 30 the screw M and the lower ends of the rear spring, H, are raised and lowered, whereby the rear end of the saddle is adjusted up and down and backwardly or forwardly. The upper portions, o, of the spring branches h are turned 35 backwardly and follow the rear edge of the cantle which they support, as represented in Figs. 1 and 3. The inner ends of the upper portions, o, are provided with right and left screw-threads, which are connected by a screw- 40 sleeve or coupling, P. The latter permits the ends o' of the spring branches to be drawn together or to be expanded.

Q represents the longitudinal opening formed in the seat B, and extending to the 45 rear edge thereof. The rear edges of the seat are lapped around the ends o' of the spring branches, and are secured thereto by rivets.

q represents a lacing-cord passed through lacing-holes q', formed along the rear edges of 50 the opening Q, and serving to tighten the rear portion of the seat when the width of the cantle-frame has been adjusted by the screw-sleeve P. If one of the spring branches h should break, it can be easily replaced without 55 renewing the entire spring.

I claim as my invention—

1. The combination, with the frame and saddle, of a screw-threaded supporting-standard pivoted to the frame, and a screw-nut connected with the saddle and engaging with said standard, substantially as set forth.

2. The combination, with the frame and saddle, of a screw-threaded supporting-standard pivoted to the frame, a screw-nut applied to 65 said standard, and a bolt pivoted to said nut

and connected with the saddle, substantially as set forth.

3. The combination, with the frame and saddle, of a screw-threaded supporting-standard pivoted to the frame, a screw-nut applied to 70 said standard, a bolt pivoted to the nut and connected with the saddle, and a spring applied to said bolt, substantially as set forth.

4. The combination, with the frame and saddle, of a socketed pommel-plate secured to the 75 saddle, a spring seated in said plate, a bolt passing through said spring, a screw-nut pivoted to said bolt, and a screw-threaded supporting-standard pivoted to the frame and engaging with said screw-nut, substantially as 80 set forth.

5. The combination, with the frame and saddle, of a screw-threaded supporting-standard attached to the frame, a screw-nut applied to 85 said standard, and a bolt connecting said screw-nut with the saddle and attached to the screw-nut near one end thereof, substantially as set forth.

6. The combination, with the frame and saddle, of a screw-threaded standard attached to 90 the frame, a screw-nut applied to said standard and provided near one end with a perforated ear, and a bolt connected with the saddle and pivoted to the ear of the screw-nut, substantially as set forth.

7. The combination, with the frame and saddle, of a screw-nut connected with the saddle, and a screw-threaded supporting-standard, D, pivoted to the frame and provided with a cross-piece, d', resting on the frame, substantially as set forth.

8. The combination, with the frame and saddle, of a supporting-standard pivoted to the frame, a bolt pivotally connected at its front end with said standard and extending rearwardly therefrom underneath the saddle, and a spring applied to said bolt and connected with the saddle, substantially as set forth.

9. The combination, with the frame and saddle, of a pommel-plate provided in its under 110 side with a longitudinal socket, a spring arranged lengthwise in said socket, and a pommel-support connected with the frame and with said spring, substantially as set forth.

10. The combination, with the saddle, of a 115 supporting-spring composed of two similar branches having their upper and lower ends screw-threaded, and screw-sleeves connecting the adjacent ends of the branches, substantially as set forth.

11. The combination, with the saddle and frame, of a supporting-spring composed of two similar branches secured with their upper ends to the saddle, and having their lower ends screw-threaded and attached to the frame, 125 and a screw-sleeve connecting the lower ends of said branches, substantially as set forth.

12. The combination, with the saddle and frame, of a supporting-spring composed of two similar coiled branches having their upper 130

ends attached to the saddle, a supporting-plate secured to the frame and receiving the coils, and a coupling connecting the lower ends of the branches of the spring, substantially as set forth.

13. The combination, with the saddle and frame, of a supporting-spring composed of two similar coiled branches secured with their upper ends to the saddle, and having their lower ends connected by a coupling and supported on the frame, and an adjusting-screw, whereby the spring can be raised and lowered, substantially as set forth.

14. The combination, with the saddle and frame, of a supporting-spring composed of two similar branches secured with their upper ends to the saddle, and having their lower ends connected by a coupling and supported on the frame, and an adjusting-screw passing through said coupling, substantially as set forth.

15. The combination, with the saddle and

frame, of a supporting-spring composed of two similar branches secured with their upper ends to the saddle, and having their lower ends screw-threaded, a threaded coupling-sleeve 25 connecting said ends, a plate attached to the frame and supporting the spring, and an adjusting-screw working in said coupling-sleeve and resting on the supporting-plate, substantially as set forth.

16. The combination, in a saddle, of an expandible seat and an expansible frame composed of the two side pieces secured to the seat and connected at their inner ends by a screw-coupling, substantially as set forth.

Witness my hand this 15th day of December, 1886.

EMMIT G. LATTA.
